UNITED STATES PATENT OFFICE

151,060

DESIGN FOR A TOILET TRAY

Zebinia E. Marvin, Jr., Dallas, Tex.

Application April 15, 1947, Serial No. 138,422

Term of patent 3½ years

(Cl. D86—10)

To all whom it may concern:

Be it known that I, Zebinia E. Marvin, Jr., a citizen of the United States of America, residing at Dallas, in the county of Dallas and State of Texas, have invented a new, original, and ornamental Design for Toilet Trays, of which the following is a specification, reference being had to the accompanying drawing, forming a part thereof.

Fig. 1 is a front elevational view of a toilet tray, showing my new design,

Fig. 2 is a top plan view of the toilet tray,

Fig. 3 is a rear elevational view of the toilet tray,

Fig. 4 is an underside plan view of the toilet tray, and

Fig. 5 is an end elevational view of the toilet tray.

I claim:

The ornamental design for a toilet tray, as shown.

ZEBINIA E. MARVIN, JR.
